EXTRUDED STRUCTURAL MEMBER OR
SIMILAR ARTICLE

Eugene B. Le Van, 15858 El Paseo Drive,
Whittier, Calif. 90603

Filed Mar. 8, 1972, Ser. No. 233,011

Term of patent 14 years

Int. Cl. D25—01

U.S. Cl. D13—6

FIG. 1.

FIG. 2.

FIG. 3.

FIG. 4.

FIG. 5.

FIG. 1 is a top plan view of an extruded structural member or similar article showing my new design;

FIG. 2 is an elevational view of one side thereof;

FIG. 3 is a bottom plan view of the same;

FIG. 4 is an elevational view of the side opposite that seen in FIG. 2; and

FIG. 5 is a transverse section taken on line 5—5 of FIG. 1.

The design has indeterminate length.

I claim:

The ornamental design for an extruded structural member or similar article, as shown and described.
